UNITED STATES PATENT OFFICE.

JAMES P. DOVEL AND CHARLES C. GLIDDEN, OF BIRMINGHAM, ALABAMA.

AMALGAMATOR.

1,123,116.

Specification of Letters Patent. Patented Dec. 29, 1914.

Continuation of application Serial No. 728,729, filed October 30, 1912. This application filed May 11, 1914. Serial No. 837,673.

To all whom it may concern:

Be it known that we, JAMES P. DOVEL and CHARLES C. GLIDDEN, citizens of the United States of America, residing at Birmingham, 5 in the county of Jefferson and State of Alabama, have invented certain new and useful Improvements in Amalgamators, of which the following is a specification.

Our invention relates to concentrators 10 which comprise a revolving bowl into which the crushed ore or sand to be treated is introduced with water, and the sludge thus formed is spread into a thin mass by the spinning action of the bowl and moved continuously toward and discharged over the 15 periphery of the bowl. The centrifugal action concentrates the free gold in the bottom stratum of the moving mass of sludge.

The object of our invention is to produce 20 an effective means to catch the gold, thus concentrated, by means of mercury and consists essentially in the provision of means which will bring the mercury and the concentrated gold into effective contact and prevent 25 the loss of mercury from the bowl. We have found that this is best effected by providing the bowl with annular grooves adapted to receive the mercury and in providing an amalgamating surface to contact with 30 the mercury in or as it tends to escape from, each groove and also providing non-amalgamated surfaces between the grooves. As the mercury in the grooves will flow circumferentially therein, due to its lag, it will 35 tend to globularize and ride over the particles of matter that may collect in the grooves. The centrifugal action of the bowl will tend to quickly dislodge from the grooves the globules of mercury, when 40 formed, and let them escape. The amalgamated surfaces, which contact with the mercury in the grooves, constitute the most important factor in preventing globularization and the non-amalgamated surfaces inter- 45 posed between the grooves are adapted to prevent the mercury spreading out over the face of the bowl and escaping. The arrangement of grooves in the bowl and the character of the amalgamated and non- 50 amalgamated surfaces may be widely varied to suit different operating conditions.

Our invention further comprises the details of construction and arrangement of parts hereinafter more particularly de- 55 scribed and claimed, reference being had to

the accompanying drawings, in which the preferred embodiments only of our invention are illustrated, and in which:—

Figure 1 is a vertical sectional elevation through our improved concentrator. Fig. 2 60 is an enlarged sectional view of part of the bowl showing more clearly the arrangement of amalgam rings in the mercury grooves. Fig. 3 is a view similar to Fig. 2 showing amalgam riffle plates substituted for the 65 amalgam rings.

Similar reference numerals refer to similar parts throughout the drawings.

In the forms illustrated, our invention is shown comprising a dished or concave bowl 70 1 having a series of annular grooves 2 in its inner face and having secured to the underside of its bottom 3 a boss 4. The tailings or crushed ore and water pass downwardly centrally into the bowl through a discharge 75 pipe 5 leading from the hopper 6. The bowl is rotatably supported by a shaft 7 which screws into the boss 4 and turns in bearings 8 and 9 in the stand or support 10 for the apparatus. The shaft 7 has fixed thereon 8 collars 11 which rest upon the bearings 8 and 9 and support the bowl, which is rotated by a pulley 12 keyed to the shaft 7. The bowl is disposed within a suitable casing 13 having an opening through which the shaft 7 85 passes and which is surrounded by a flange 14 to prevent the escape of tailings therethrough as the same pass down along the inclined bottom 15 of the casing and out through the chute 16. This casing 13 is supported by angle irons 17 and 18 which are fastened to the base 10. The top portion of the casing is open so that the action of the ore in the bowl may be watched.

In each of the grooves 2 we interpose an 95 annular ring 21 of silver or other metal which will amalgamate, or we may use metal strips 22 which will project slightly above the inner face of the bowl so as to form what we term amalgamated riffles. The rings 100 and strips are preferably split so that they can be collapsed and inserted in the grooves 2. When the loose ends of the rings or strips have been forced outwardly until they abut, the rings or strips will be securely held 105 in place in the grooves and, in the case of the strips, will preferably stand against the outer wall of the groove, leaving the mercury, with which the grooves are filled, exposed therein on the side of the strip where 110

it will most effectively act on the ore when arrested in its outward movement by the riffles. The inner surface of the bowl itself, or at least that part thereof between the 5 grooves is non-amalgamating material.

In practice, the crushed ore or tailings and water in the form of sludge move down by gravity through the pipe 5 and fall upon the center of the rapidly revolving bowl 1. 10 The sludge is thereupon immediately acted upon by centrifugal force which moves it outwardly and upwardly in a thin sheet over the grooved surface of the bowl until it is discharged over the periphery of the 15 bowl when it is caught by the casing 13 and is discharged through the chute 16. The centrifugal action also tends to concentrate the heavier particles of gold against the surface of the bowl. The grooves 2 having the 20 amalgam ring or strip inserted therein and having been filled with mercury, the sludge will pass successively over the bodies of mercury and the gold concentrated in its under layer will be readily amalgamated by contact with the successive bodies of mercury or with the rings or plates 21 and 22. Without the use of the amalgamated rings 21 the mercury in the grooves would tend to form 25 into globules and pass out freely with the tailings, while by using these rings they not only more effectively arrest the particles of gold and cause the amalgamation thereof with the mercury, but they also effectively prevent the globularization of the mercury 30 and hence the waste thereof, which would materially interfere, as has been demonstrated by experiments, with the effective or even practical operation of the apparatus.

The important function of the amalgamated surfaces is obtained when the same will contact in any manner with the mercury in the grooves, and hence we regard the structure of such surfaces and the manner of attachment to the bowl as capable of being widely varied and, as before stated, it is not of essential importance that the amalgamated rings or strips should serve the additional function of riffles.

The means to prevent the globularization 50 of the mercury in the grooves of a rotating bowl are of peculiar importance as in rotating tables of that character the mercury being fluid will tend to circulate in the grooves and this tendency increases its liability to form in globules and also for the globules to ride over particles of sand and ore, which latter tendency is prevented where the amalgam plate holds the mercury against globularization and causes it to keep 55 under all the moving particles which are lighter, thereby effectively displacing them and preventing the grooves filling up with lighter material which would involve an immediate and substantial loss in mercury.

60 The amalgamated surface of the bowl be-

tween the grooves prevents the tendency of the mercury to spread from groove to groove and escape.

Without intending to limit ourselves to the details of construction shown, what we 70 claim as new and desire to secure by Letters Patent, is:—

1. An ore concentrator comprising a rotatable concentrating-table having a series of annular grooves therein containing each 75 a body of mercury and disposed transversely to the line of flow of the material to be treated, said table having non-amalgamated surfaces interposed between the grooves, and said grooves having amalgamated surfaces with which the mercury therein contacts and which tends to prevent the globularization of the mercury while in the 80 grooves.

2. An ore concentrator comprising a rotatable concentrating-table having a series of annular grooves formed therein containing each a body of mercury and disposed transversely to the line of flow of the material to be treated, the surface of said table 90 over which the ore passes in moving successively over the grooves being formed of non-amalgamated material, and means on said table and in contact with said mercury in the grooves, which means is adapted to 95 prevent the globularization of the mercury in said grooves.

3. An ore concentrator comprising a rotary dished concentrating bowl having its inclined side surface of non-amalgamated 100 material which is annularly grooved to provide a series of spaced ring-shaped troughs for the reception of mercury, there being mercury in said troughs, an amalgamating means on said side surface which are disposed with reference to said troughs to 105 maintain a contact with the mercury therein under operating conditions.

4. An ore concentrator comprising a rotatable concentrating-table formed of non-amalgamated material and having grooves formed therein and disposed transversely to the line of flow of material to be treated, said grooves containing a body of mercury, strips of amalgamated metal which are introduced into the body of mercury in said 110 grooves and detachably held in place in said grooves.

5. An ore concentrator comprising a rotatable concentrating-table having a series 115 of annular grooves therein, the walls of which are of non-amalgamated material and which are filled with mercury, and amalgamated rings adapted to be inserted in said grooves and frictionally held in place therein, as and for the purposes described.

6. An ore concentrator comprising a rotatable concentrating-table having grooves formed therein and disposed transversely to the line of flow of the material to be treated, 120

said grooves having walls of non-amalgamated material and containing a body of mercury, and a strip of amalgamated material inserted in said grooves and brought into contact with the mercury, as and for the purposes described.

7. An ore concentrator comprising a rotatable circular concentrating-table of dished form having a series of annular grooves therein, and split amalgam rings set in said grooves and removably fixed in position therein.

8. In an ore concentrator, the combination of a rotary concentrating-table having a series of grooves therein filled with mercury, and amalgamated plates in said grooves and projecting above the grooves to form riffles.

9. In an ore concentrator, the combination of a rotary concentrating-table having a series of grooves therein each containing a body of mercury, and amalgamated riffle plates set in said grooves at the far side thereof with reference to the movement of the ore to be concentrated, said plates contacting with the mercury in their respective grooves.

In testimony whereof we affix our signatures in presence of two witnesses.
